UNITED STATES PATENT OFFICE.

JOSEPH E. EVANS, OF BEDFORD, INDIANA, ASSIGNOR OF ONE-FOURTH TO OLIVER N. CLIFFORD, OF ST. LOUIS, MISSOURI, AND ONE-FOURTH TO JASPER O. GYGER, OF BEDFORD, INDIANA.

SUSPENSION DEVICE FOR EQUALIZING THE STRAIN ON ELEVATOR CABLES.

Application filed May 29, 1919, Serial No. 300,726. Renewed January 23, 1922. Serial No. 531,314.

To all whom it may concern:

Be it known that I, JOSEPH E. EVANS, a citizen of the United States, residing at Bedford, in the county of Lawrence and State of Indiana, have invented certain new and useful Improvements in Suspension Devices for Equalizing the Strain on Elevator Cables, of which the following is a specification.

10 In elevators or lifts which are widely used for transferring passengers and freight from one floor of a building to another, the elevator car is usually suspended from a group of cables which run over a grooved pulley at the top of the elevator shaft, the car being counterbalanced by weights also suspended from cables running over the pulley at the top of the shaft. While the construction and arrangement of the parts of 15 the hoisting mechanism varies among various manufacturers of such appliances, it is in all cases usual to employ a group of several cables, generally about a half dozen in number to sustain the car. These cables, 20 because of unavoidable variations in manufacture, are liable to stretch unequally, so that if they are all rigidly secured to the car they do not at all times sustain an equal load, with the result that the one which is 25 the most unyielding and bears the greatest part of the load is apt to break. It is the object of my invention to provide an efficient and desirable suspension and equalizing means intermediate the car and the group 30 of cables which will equalize the load between the different cables and which, if any cable should break, through a defect or for any other cause, will act to distribute the load equally among the remaining cables.

35 My invention consists in the novel combination and arrangement of cooperating parts of the equalizing device hereinafter described, and in various novel and desirable structural features which will be apparent 40 from the description given. In the appended claims I have pointed out the essential elements of my invention, it being understood, however, that the specific structure described, and which is illustrated in the 45 accompanying drawings, is but one exemplification of my invention, and that changes 50 therein, transposition in the arrangement of

parts, the substitution of equivalents, and by variations in form and construction of elements, may be made without departure 55 from the scope of the claims or the substance of my invention.

In the drawings Fig. 1 is a side view of my novel equalizing device, showing associated parts of the suspension pulley, 60 cables and elevator car; Fig. 2 is a vertical section on the line 2—2 of Fig. 1 and on a larger scale, showing the construction of the pistons and cylinders of the device; Fig. 3 is a horizontal section on the line 3—3 65 of Fig. 1, showing the arrangement of the equalizer bars; Fig. 4 is a fragmentary detail showing in perspective the base portion of one of the pistons or plungers; and Fig. 5 is a front view (at right angles to the 70 position of Fig. 1), illustrating a modified form of my invention.

The same reference characters indicate the same parts in all the figures of the drawings.

Describing first the preferred form of my 75 device illustrated in Figs. 1 to 4, the cables 1 by which the car 2 is suspended extend at the top in a loop which passes twice over the top of the suspension pulley 4 at the top of the elevator shaft and once below the 80 idler pulley 5 which is arranged immediately below the suspension pulley. The suspension pulley will thus be formed with twice as many grooves as the number of cables employed—in the present instance six cables 85 being used,—and the cables may be divided into two groups connected respectively to the opposite ends of a set of equalizer bars 6 which are connected to the pistons or plungers of the suspension device. 90

Broadly speaking, my device consists of a framework secured to the elevator car and supporting and including three inverted intercommunicating oil-filled cylinders and three plungers or pistons having base portions at their lower outer ends pivoted to equalizing bars which are connected at their opposite ends to the members of the group of cables, which are separated into two parts. In the present instance the cylinder frame 95 includes a series of guide-bolts 7, eight in number, having upper reduced cylindrical portions 8 and lower cylindrical portions 9, the device being secured to top of the eleva- 100

tor car by means of the lower portions 9. To this end a stop plate 10, orificed to engage the said reduced lower portions and seat against the shoulders at the end of the central portions, is provided, and also a clamping plate 11 which, by clamping nuts 12 engaging the threaded lower end of the lower portions, may be drawn towards the plate 10 to clamp the device to a suitable portion of the roof of the car, as for instance, a pair of channel irons 13 forming a part of the framework of the car structure.

The lower head plate 14 of the cylinders 15 is orificed to engage the upper reduced portions 8 of the bolts and seat against the shoulders at the upper end of their central portion, and a set of clamping nuts 16, cooperating with the upper threaded ends of the bolt portions 8 is employed to clamp an upper head plate 17 against the cylinders, which latter seat in annular seats or recesses formed to receive them in the plates 14 and 17, and thus secure the parts together. The upper heads are formed with ports 18 affording free communication between the cylinders, and also with a filling orifice and a vent, both normally closed by suitable screw plugs.

The plungers 20 are each provided at the top with a pair of cup leathers 21, supported by metal cups 22, to seal the cylinder completely and prevent the escape therefrom of the oil with which they are filled. The oil most suitable for use in my device is a relatively heavy mineral oil, although other varieties of oil, or other fluids, may be employed. The lower end of each piston is enlarged, as shown, and the enlarged base 23 is grooved vertically to slidingly engage the guide bolts 7. The bases 23 of the pistons are also slotted to each receive a pair of the equalizer bars 6 above mentioned, the members of each pair being bolted or otherwise secured together so that in effect they together form a single equalizer bar having forked ends which are orificed and adapted to receive a pivot block 24 formed with gudgeons journaled in the sides of the fork. The cables 1 are connected to the bars 6 by socket bolts 25, the lower threaded ends of which extend through orifices in the blocks 24 and are equipped with bearing nuts 26 and lock nuts 27. Each pair of equalizer bars is pivoted to the base of its associated plunger by means of a cross pin 28 secured against displacement by a set screw 29, and, as will be seen by reference to Fig. 3, the arrangement of the slots of the bases 23 of the plungers and their pivotal support of the bars 6 is such that the latter have a slightly oblique and staggered arrangement, so that the cables, divided in alternation into two groups, may exhibit no lateral pull and will track correctly into their respective grooves on the pulley.

It is obvious that the strain on the two cables at opposite ends of any given pair of bars 6 will be equal, since the downward stress on the plunger is exerted midway between them, and this will be true although one may have stretched so that the bars do not stand in horizontal position. It is further obvious that since the plungers are of equal size, and the cylinders communicate with each other, the weight of the car will be equally distributed between the plungers, whether they stand at the same or different heights in the cylinders. The weight of the car will therefore be distributed equally among all the connected cables. Should any cable break, the proportion and arrangement of the parts is such that the end of the pair of equalizer bars to which it was connected will contact with the stop plate 10, and the weight of the car will be equalized between the remaining five cables.

While my invention as above explained was devised with particular reference to its use as an equalizing device for the suspension of elevator cars or lifts, it is equally applicable to the counterbalance of such cars, and is also capable of being used generally in any situation when it is desirable to equalize the strain upon a group of cables used to sustain or hoist anything in a similar manner.

In the modification shown in Fig. 5, the inner guide bolts, marked 30, terminate at the level of the stop plate 10, which is orificed to provide sockets which receive the lower ends of such bolts and restrain them against lateral movement. Preferably, the outer bolts, marked 32, are heavier and larger than the inner bolts, inasmuch as the former sustain the entire weight of the car and it is unnecessary to make the inner bolts equally heavy.

I claim:

1. A suspension device for connecting an elevator car to a group of cables arranged to engage a supporting pulley, said device comprising a plurality of intercommunicating cylinders secured to the car, a corresponding plurality of pistons arranged in said cylinders, and equalizing bars pivotally connected at their centers to said pistons and at their opposite ends to separate cables, said bars being arranged transversely of a vertical tangential plane passing through the periphery of said supporting pulley.

2. A suspension device for connecting an elevator car to a group of cables arranged to engage a supporting pulley, said device comprising a plurality of intercommunicating cylinders, a corresponding plurality of pistons arranged in said cylinders, one of said groups of cooperating members being secured to the car, and a plurality of equalizing bars respectively pivotally connected at their centers to the members of the other

of said groups of cooperating members and also connected at their opposite ends to separate cables, said bars being arranged transversely of a vertical tangential plane passing through the periphery of said supporting pulley.

3. A suspension device according to claim 1 in which the equalizing bars are arranged obliquely with respect to a plane passing axially through the cylinders and to the tangential plane passing through the periphery of the supporting pulley, whereby the opposite cables will stand in staggered relation and track with equally spaced cables.

10 4. A suspension device for connecting an elevator to a group of cables, comprising a plurality of intercommunicating cylinders secured to the car and provided with downwardly extending guide bolts, a corresponding plurality of pistons arranged in said cylinders and having their lower ends arranged to slidingly engage said guide bolts, and means for connecting said cables to the lower ends of said pistons.

15 5. A suspension device for connecting an elevator to a group of cables, comprising a plurality of intercommunicating cylinders secured to the car and provided with downwardly extending guide bolts, a corresponding plurality of pistons arranged in said cylinders and having their lower ends arranged to slidingly engage said guide bolts, and equalizing bars pivotally connected at their centers to said pistons and at their opposite ends to separate cables.

20 6. A suspension device according to claim 4 in which the lower ends of said pistons are enlarged and formed with vertical grooves engaging said guide bolts.

25 7. A suspension device according to claim 5 in which the cylinders are secured to downwardly extending guide bolts and the lower ends of said pistons are enlarged and formed with vertical grooves engaging said guide bolts.

30 8. A suspension device according to claim 5 in which the ends of the equalizing bars are arranged to bring up against a stop upon the car at a fixed limit of downward movement.

35 9. A suspension device according to claim 5 in which the equalizing bars are forked at their opposite ends and the forks provided with bearings and in which pivot blocks formed with gudgeons arranged to engage said bearings are provided.

40 10. A suspension device according to claim 5 in which the equalizing bars are arranged in pairs of members secured together and spreading to form forks at the opposite ends of a pair and in which the forks are orificed and pivot blocks formed with gudgeons arranged to engage said orifices are provided.

45 11. In a device of the character described,

a plunger structure comprising an upper head plate formed with a series of seats and intercommunicating ports, a lower head plate formed with a like series of seats, a corresponding series of tubular cylinder members arranged intermediate said upper and lower seats, a plurality of bolts arranged to clamp said upper and lower plates upon said cylinder members, and a series of plungers in said cylinders, said bolts having depending portions arranged to be slidingly engaged by said plungers.

50 12. A plunger structure according to claim 10 in which the guide bolts are extended below the portions thereof arranged to be engaged by the plungers and are equipped with upper and lower clamping members.

55 13. A plunger structure according to claim 10 in which the depending lower portions of said guide bolts are of larger diameter than the upper clamping portion and the lower head plate abuts against the annular shoulders at the top of such lower portions.

60 14. A suspension device for connecting an elevator car to a group of cables arranged to engage a supporting pulley, said device including a plurality of parallel equalizing bars respectively pivotally connected at their centers to the car and arranged to jointly support such car, said bars being connected at their opposite ends to separate cables and being arranged transversely and obliquely with reference to a vertical tangential plane passing through the periphery of the supporting pulley, whereby the opposite cables will stand in staggered relation and track with equally spaced pulley grooves.

65 15. A suspension device according to claim 14 in which the equalizing bars are forked at their opposite ends and the forks provided with bearings and in which pivot blocks vertically orificed for attachment to said cables and formed with gudgeons arranged to engage said bearings are provided.

70 16. A suspension device according to claim 14 in which the equalizing bars are forked at their opposite ends and the forks provided with bearings and in which blocks arranged to pivotally engage said bearings are provided for attachment to said cables.

75 17. A suspension device according to claim 14 in which the equalizing bars are arranged in pairs of members secured together and spreading to form forks at the opposite ends of a pair and in which the members of the forks are orificed and pivot blocks formed with gudgeons arranged to engage said orifices are provided.

80 18. In a suspension device for connecting an elevator car to a plurality of cables, said device including an equalizing bar pivotally connected at its center to the car and formed with orificed forks at its opposite ends, a pair of pivot blocks respec-

tively seated in said forks and formed with
gudgeons arranged to pivotally engage the
orifices of said forks.

19. In a suspension device for con-
necting an elevator car to a plurality of
cables, said device including an equalizing
bar pivotally connected at its center to the
car and formed with orificed forks at its op-

posite ends, a pair of pivot blocks respec-
tively seated in said forks and formed with 10
gudgeons arranged to pivotally engage the
orifices of said forks, said blocks being ver-
tically orificed for attachment to a pair of
cables.

JOSEPH E. EVANS.
